UNITED STATES PATENT OFFICE.

ANDRO DURCHIN, OF KELAYRES, PENNSYLVANIA.

DIRECTION INDICATOR.

Application filed September 22, 1921. Serial No. 502,394.

This invention relates to improvements in direction indicators adapted for use on motor vehicles and the like to indicate to anyone following the vehicle the intention 5 of the operator.

Another object of the invention resides in the provision of an electrically operated indicating means arranged at the rear end of the vehicle and controlled from a point in 10 close proximity to the driver's seat, so that said indicating means may be readily actuated.

Still another object of the invention is to provide a device which may be as readily 15 seen at night as in the daytime, so that danger of rear end collisions may at all times be avoided.

A further object of the invention is to provide an electro-magnetically operated 20 semaphore arm, combined with electric lamp bulbs arranged so that the whole may be enclosed in a single housing which may be mounted as a unit on the vehicle.

A still further object of the invention is 25 to provide a resilient means for normally holding the semaphore arm in vertical position and prevent the exposure of the words "Right" and "Left", so as to avoid any possibility of confusing the signals.

With these and other objects in view which 30 will be fully set forth in the following specification, the invention consists in the novel construction, combination and arrangement of parts which will be set forth 35 in the annexed specification, and illustrated in the accompanying drawing, in which

Figure 1 is a view of this device in use,

Figure 2 is a rear face view of the device,

40 Figure 3 is a view similar to Figure 2, with the cover plate removed,

Figure 4 is a horizontal sectional view taken on line 4—4 of Figure 3,

Figure 5 is a view showing the wiring 45 diagram of the device.

Referring to the drawings by characters of reference, the numeral 10, designates the housing of the device which is provided with a removable cover plate 11 having the light openings 12, 13, and 14 arranged therein. 50 Openings 15, 16, and 17 are formed in the cover plate through which the words "Right", and "Left" are visible according to the position of the semaphore arm. As shown the casing is slotted to permit the free end of said arm to project outwardly and both the back wall of the casing and of the

the cover plate are provided with bearing members 18 in which the spindle 19 is journaled.

Secured adjacent the forward end of the 60 spindle 19 and extending at right angles thereto, is the semaphore arm 20 formed from a flat transparent plate, the outer end of which projects through the slot in the casing and is enlarged as at 21 to provide a 65 readily visible portion upon which the word "Look" or some similar designation may be displayed. The arm 20 is provided adjacent its outer end with an opening 22 which is adapted to register with the openings 12, 13, 70 and 14, depending upon which position the arm is in. It will also be apparent that the words "Right", and "Left", will be rendered visible when their respective lights are lighted. 75

In order to control the various movements of the arm 20, solenoids 23 and 24 are provided having the sliding cores 25 which are normally forced inwardly by means of springs 26. The outer ends of 80 these cores are enlarged to provide rack bars 27 which engage pinions 28 secured to the spindle. It will thus be seen that when the solenoid 23 is energized, the semaphore arm will be swung downwardly into 85 the position indicating that the operator intends turning to the left and at the same time the word "Left" carried by the semaphore arm will become visible through the opening 16 in the cover plate of the housing. 90 Upon energizing the opposite solenoid, it will be evident that the arm will move into the opposite indicating position and the word "Right," will appear in the opening 17 in the cover plate 11. As illustrated in 95 Figure 2, the openings 12, 13, and 14, are provided with covers of glass or similar transparent material and are preferably colored as indicated in the drawings, so that when the lamp bulb to the left is illuminated it will show red, while the opposite light will show green upon illumination and the upper glass is clear. A separate illuminating device such as lamp bulbs 29 is provided for each opening 12, 13, and 14 100 and each bulb is controlled by an individual switch mounted on a switch-board on the dash-board of the car. It is to be understood that this switch-board is to be within easy reach of the vehicle operator and carries the 105 switches 30 for controlling the energization of the solenoids. While the device is shown 110

as being provided with an individual power source, it may be connected with the starting and lighting system usually placed on modern cars.

What I claim and desire to secure by Letters Patent is:—

1. The combination of a slotted housing provided with a plurality of openings, with a semaphore arm bearing different signaling indicia arranged in parallel rows one over the other, said openings being arranged to show different signals upon reversal of position of the arm, and means for operating

said arm to assume right and left hand horizontal positions.

2. The combination of a slotted housing having an aperture at the right and left hand side of its face, with a semaphore arm of transparent material, an enlarged portion on said arm extended through the slot in said housing, and means for reversing the horizontal position of said arm to assume certain selected positions.

In witness whereof I affix my signature.

ANDRE DURCHIN.
